HAIRPIN

Edith Fromm Barth, New York, N. Y., assignor
to Marco Bergmann, New York, N. Y.

Application August 31, 1940, Serial No. 354,965

3 Claims. (Cl. 132—52)

This invention relates to hairpins.

A well known difficulty with present hairpins is that the pins often become loose and work their way out of the hair. Women are often seen pushing the hairpins back into the hair when they become loose and stick out of the hair. Hairpins have been constructed in various ways in attempts to keep them from coming out of the hair, or from loosening, and such efforts have not been very successful. The usual hairpin is U-shaped having a pair of arms or prongs interconnected by a curved or bent back portion. When the prongs of usual hairpins are forced into the hair, they will not clamp the hair in a manner to keep the hairpins firmly in the hair. It is therefore an object of this invention to provide a hairpin which may be applied to the hair in the manner of the usual hairpin, but having highly improved means to prevent the hairpin from falling out or becoming loose from the hair.

A further object of this invention is to provide a hairpin of the character described, having means to resiliently grip the hair, which will be easy to apply and remove without any more manipulation than is necessary with the usual hairpin, but which will nevertheless so grip the hair that it will not project from the hair or work its way out of the hair.

Still another object of this invention is to provide a simple and neat and durable hairpin of the character described, which shall be relatively inexpensive to manufacture, and which shall yet be practical and efficient to a high degree.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawing, in which is shown various possible illustrative embodiments of this invention,

Fig. 1 is a perspective view of a hairpin embodying the invention;

Fig. 2 is a side elevational view thereof;

Fig. 3 is a view similar to Fig. 1, but illustrating a modified construction;

Fig. 4 is a side elevational view of the hairpin shown in Fig. 3;

Fig. 5 is a view similar to Fig. 3, but illustrating the wedging of the hair between adjacent prongs of the hairpin;

Fig. 6 is a cross-sectional view taken on line 6—6 of Fig. 5;

Fig. 7 is a top plan view, partly in cross-section, of a pin embodying the invention, and illustrating a modified construction; and

Fig. 8 is a cross-sectional view taken on line 8—8 of Fig. 7.

Referring now in detail to the drawing, 10 designates a hairpin embodying the invention. The hairpin 10 is generally U-shaped having arms 11 interconnected by a curved central or intermediate portion 12. Each of the arms 11 comprises a pair of prongs 13 and 14, joined together at the curved portion 12. The pin 10 may be made of metal wire or any other material having some resiliency.

In Figs. 1 and 2, the pin 10 is made of two metal wires twisted together at the middle and bent to form the curved portion 12, the outer ends of the wires constituting the prongs 13 and 14. The prongs 13 and 14 of each arm 11 diverge somewhat so that when the hairpin is pushed into the hair, some hair will become wedged between the prongs and gripped thereby, to prevent the hairpin from accidentally loosening from the hair.

The prongs 13 and 14 may have corrugated or wavy portions 13a and 14a. The prongs, moreover, may be of any other desired shape.

Instead of two wires being twisted together at their mid portions, as shown in Figs. 1 and 2, three or more wires may be so twisted, so that each arm comprises more than two prongs.

It will now be understood that the hairpin 10 has generally the shape of an ordinary hairpin, that is, U-shape, and comprises a pair of arms interconnected by a curved portion, and the hairpin may be handled and applied in the usual manner, being adapted to be embedded or pushed into the hair in a manner no different than with an ordinary hairpin.

It is the provision of a plurality of prongs in each arm joined at one end and adapted to resiliently grip the hair, which prevents the improved hairpin from coming out.

The wires of which the hairpin is made may be joined together at their mid portions in various ways. In Figs. 3 and 4, the wires of the hairpin 10a are joined together by soldering them or welding them at the curved portion 12a, thus forming arms 11a, each consisting of double prongs 18. Thus, in Figs. 3 and 4, two ordinary hairpins 19 are placed side by side in superimposed positions, and the curved portions are welded or soldered together, or joined together

in any other suitable manner, indicated at 12a. The prongs slightly diverge.

As shown in Figs. 5 and 6, some of the hair 20 is wedged between the prongs 18 in each arm 11a.

In Figs. 7 and 8, there is shown a hairpin 10b embodying the invention, comprising a pair of hairpins 22 placed together in superimposed position and joined together at their upper curved portions by a U-shaped clip 23. The hairpin 10b thus has a pair of arms 24, each constituting a pair of prongs 25. The prongs 25 may have outwardly curved portions 26 to form a space 27 between said prongs to receive some of the hair. The prongs 25 may be somewhat divergent to permit hair to be wedged in between said prongs.

It will thus be seen that there is provided a device in which the several objects of this invention are achieved, and which is well adapted to meet the conditions of practical use.

As various possible embodiments might be made of the above invention, and as various changes might be made in the embodiments above set forth, it is to be understood that all matter herein set forth or shown in the accompanying drawing is to be interpreted as illustrative and not in a limiting sense.

Having thus described my invention, I claim as new and desire to secure by Letters Patent:

1. An article of manufacture comprising a pair 30 of hairpins of the same construction, each com-

prising a pair of prongs and a portion interconnecting said prongs, said hairpins being superimposed one on the other in substantial registry, and in parallel planes, and means to attach the 5 interconnecting portion of one to the interconnecting portion of the other, the prongs of one hairpin being somewhat divergent relative to the adjacent prongs of the other hairpin.

2. An article of manufacture comprising a pair 10 of hairpins of the same construction, each comprising a pair of prongs and a portion interconnecting said prongs, said hairpins being superimposed one on the other in substantial registry, and in parallel planes, and means to attach 15 the interconnecting portion of one to the interconnecting portion of the other, the prongs of one hairpin being somewhat divergent relative to the adjacent prongs of the other hairpin, said means comprising a U-shaped clip engaging the 20 interconnecting portions of said hairpins.

3. As an article of manufacture, a U-shaped member comprising a pair of hairpins of the same construction, each having a pair of prongs and a portion interconnecting said prongs, said 25 interconnecting portions contacting one another, means to attach the contacting portions of said hairpins to one another, said hairpins being superimposed one on the other in substantial registry, and the prongs of one hairpin being divergent 30 from the prongs of the other hairpin.

EDITH FROMM BARTH.
